ABSTRACT: A one- or multisteps compressing ionic-pump which comprises means for providing a chamber of higher pressure and a chamber of lower pressure, and a separating wall nonpermeable to gas is disposed between the chambers. At least one channel member extends through the wall for the transportation of an ion stream therethrough. The channel member has a large stream resistance for the gas return-diffusing from the area of higher pressure into the area of lower pressure, and a high frequency alternating field is applied in front of the entrance to the channel member in the lower pressure chamber between an anode preset in front of the separating wall and in and behind the channel member in higher pressure chamber connected cathodes, so that particles of gas do not arrive at lower pressure in the space.

ONE- OR MULTISTEPS COMPRESSING IONIC PUMP

The present invention relates to a one or multistep compressing ionic pump.

For the production of a high vacuum, in addition to propellant pumps (injector pumps and diffusion pumps), molecular pumps and pumps which suck up the permanent gases and vapors by means of condensation at corresponding lower temperature (by example Kryo pumps), and also the so-called ionic pumps.

In accordance with an organization principle, one distinguishes between compressing and noncompressing pumps. Compressing vacuum pumps bring about by means of one or a plurality of compressing steps a pump effect, while in case of noncompressing pumps, the gas particles to be removed condense on a solid wall or are bound physically or chemically by other means.

Also in ionic pumps, these two groups can be distinguished: The pumps of the second-mentioned type, the so-called ionic pumps, which are divided depending upon the principles and means to be used in ionic-getter evaporation pumps and ionic-getter diffusion pumps, obtain the pump effect by ionization of the gas and vapor-molecules and transportation of these ions by means of electromagnetic fields to solid walls, to which they are physically or chemically bound.

In compressing ionic pumps, however, the ionic stream which determines the sucked-off gas quantity is transported by means of electromagnetic fields into areas of higher pressure. The difference in pressure is brought about due to a difference in the ionic stream and of the return diffusion stream from the area of higher pressure. In order that a pressure difference is brought about at all, the ionic stream must be greater than the gas stream diffusing into the area of lower pressure. The first compressing ionic pump originates from R. Champeix (Compt. rend. acad. sci. July 3, 1950, see also R. Champeix, *Physics and Techniques of Electron Tubes*, Vol. I, *Principles of Vacuum Technique*, Pergamon-Press 1961, p. 129 f.) and another from H. Schwarz (Le vide, No. 42, p. 1263, 1952, see also M. Pirani and J. Yarwood, *Principles of Vacuum Engineering*, Chapman & Hall, p. 292 ff. and Champeix, a.a.O. p. 129).

It is an object of the present invention to provide an ion pump comprising a housing having a first connection adapted to be connected to a vessel to be pumped and a second connection adapted to be connected to a wort pump, a glowing electron source disposed in the housing, a separating wall dividing the housing into a lower pressure chamber and a higher pressure chamber, a channel member disposed in the separating wall, an anode catching electrons becoming free from the electron source, and cathodes connected in the higher pressure chamber. The electrons produce ions from gas from the vessel to be pumped, the channel member being permeable for the ions and substantially nonpermeable for return diffusing gas, whereby the ions are drawn in and by means of the channel member are led in the direction of the wort pump. A positive auxiliary electrode is disposed in front of the connection for the vessel to be pumped, which auxiliary electrode prevents a return diffusing of the ions into the vessel to be pumped. An anode is preset in front of the separating wall, and a high frequency alternating field is applied in front of the entrance to the channel member in the lower pressure chamber between the preset anode and in and behind the channel member in the higher pressure chamber connected cathodes so that particles of the gas do not arrive at lower pressure in the space.

It is another object of the present invention to provide an ion pump as above wherein the high frequency alternating field is connected at the channel member, so that the particles of the gas which are already in the channel member are ionized and guided back.

With these and other objects in view which will become apparent in the following detailed description, the present invention will be clearly understood in connection with the accompanying drawing, in which:

FIG. 1 is a schematic elevation in section of the Schwarz pump;

FIG. 2 is a schematic showing of an ionic pump designed in accordance with the present invention;

5 FIG. 3 is an embodiment of a one-step arrangement with high frequency; and

FIG. 4 is a schematic showing of the application of a high-frequency alternating voltage.

Referring now to the drawing, the pump of Schwarz is shown schematically in FIG. 1. The pump comprises a glow electron source F, an anode A, a repulsion electrode R, negatively charged auxiliary electrodes C and positively charged auxiliary electrodes G (ring electrodes). In the direction H is disposed the connection to the vessel to be pumped, while in the direction V the wort pump is connected. The electrons emitted from the electron source F are attracted by the anode A and ionize along on their path the gas particles by a magnetic field operating in the direction of the vessel axis, in addition to the movement in screw paths. The repulsion electrode R forces the electrons to return, whereby the ionization expectation is increased. The produced ions are attracted by the negative electrodes C, pass therethrough, and are sucked off by a wort pump. The electrode G prevents the ions from a return into the high vacuum space or chamber. With this pump, Schwarz obtained a suction speed of several liters/sec. at a pressure between $1.33 \cdot 10^{-12}$ – $1.33 \cdot 10^{-15}$ mbar., as well as a limit vacuum of about 1.3×10^{-16} mbar.

20 A pump having a greater output has been constructed by Foster, Lawrence & Lofgren (Rev. Sci. Instr. 24, 388, 1953), see thereto for example also M. Pirani & J. Yarwood p. 294 ff.

It obtains a suction speed of 3000–6000 liters/sec. at a pressure of (1–6). 10^{-16} mbar., requires, however, a power input of totally 36.5 kw. (oil diffusion pumps with about the same suction output have a power requirement of 4 to 5 kilowatt).

25 35 The first named pump of R. Champeix has a suction speed of 18 liters/sec.

The mentioned and similar arrangements have the drawbacks of slow suction output and/or low limit vacuum and enormous power input for obtaining greater suction output, respectively.

30 40 These drawbacks are the consequence of the appreciable return diffusion of the electrically neutral gas particles from the area of higher into the area of lower pressure, caused by the great passage cross section for the gas particles within the pressure steps.

45 It is one object of the present invention to provide a one or multistep compressing ionic pump which avoids the drawbacks of the known structures.

50 It is another object of the present invention to provide a one or multistep compressing ionic pump, wherein the area of higher pressure is separated from the area of lower pressure within one pressure step by arrangement of a wall nonpenetrable by the gas, in which for the transportation of the ionic stream, one channel or a plurality of parallel channels having greater flow resistance are arranged (FIG. 2). A and B identify the areas of lower and higher pressure P_1 and P_2 respectively. A wall W is arranged which separates the two areas, and a channel K is provided which leads the ionic stream from A to B. For instance, if it is formed as a tube having circular cross section, it has a diameter d , and a length l . Furthermore, the suction speed S_1 and S_2 is indicated in the areas A and B, respectively.

55 60 If I is the ionic current flowing through the channel from A to B, then the following equation applies:

$$S_1 = 2 \cdot 4 \cdot 10^{-4} \frac{I}{P_1} + \left(1 - \frac{P_2}{P_1}\right) \cdot L$$

$$S_2 = 2 \cdot 4 \cdot 10^{-4} \frac{I}{P_2} + \left(1 - \frac{P_1}{P_2}\right) \cdot L$$

65 whereby

S_1 is the suction speed in A in liter/sec.

S_2 is the suction speed in B in liter/sec.

P_1 is the pressure in B in mbar.

P_2 is the pressure in B in mbar.

I is the ion current in mA

L is the feeding value of the channel in liters/sec.

The given formulas are valid for the area of the molecular stream, whereby as a condition is given $p \cdot d < 1.33 \cdot 10^{12}$.

If one has instead of a channel only an opening in the wall (diaphragm), the cross section amounts $F \text{ cm.}^2$, it is necessary to substitute for *L* in the above stated formulas the factor 12.1 *F*.

An example will demonstrate the progress obtained with the method of the present invention.

If it is assumed that with one pressure step a pressure reduction of 10^{12} mbar. to 10^{13} mbar. is to be achieved, thus $P_1 = 10^{13}$ mbar. and $P_2 = 10^{12}$ mbar. thus also $10^{12} \times d < 1.33 \cdot 10^{12}$ for *A* and $10^{13} \cdot d < 1.33 \cdot 10^{13}$ for *B* thus $d < 1.33 \text{ cm.}$ for *A* and $d < 1.33 \text{ cm.}$ for *B*, it is thus $d < 1.33 \text{ cm.}$ to be made.

We choose a channel with $d = 0.2 \text{ cm.}$ and a length of $l = 2 \text{ cm.}$ in accordance with a known formula *L* becomes now $L = 12 \cdot (1d^2/l) f$, whereby *f* is the Clausing factor = function of $(d/l) = 0.10$.

One obtains from a table curve (see M. Wutz, Theorie und Praxis der Vakuumtechnik, Vieweg 1965, p. 114) for this ratio a Clausing factor of $f = 0.9$. One obtains thereby $L = 12 \cdot 1 (0.2^2/2 \cdot 0.9 = 0.0435 \text{ liters/sec.}$ A diaphragm of the same diameter has an area of 0.0435 cm.^2 and thus a value of L^+ of 0.53 liters/sec. thus

$$\frac{L \text{ channel}}{L^+ \text{ diaphragm}} = \frac{0.0435}{0.53} = 0.082$$

the channel feeds thus

$$\frac{1}{0.082} = 12 \text{ times worse than the diaphragm}$$

With an ionic current of 10 ma; one obtains now in *A* a suction speed of

$$S_1 = 2 \cdot 4 \cdot 10^{-4} \cdot \frac{10}{10^{-3}} \cdot \left(1 - \frac{10^{-2}}{10^{-3}}\right) \cdot 0.435 = 2.4 - 0.41 \\ = 2.0 \text{ liters/sec.}$$

In case of the diaphragm $S_1 = 2.4 - 0.53 = 2.4 - 4.75 = 2.35$, the return stream thus being three times greater than the ionic stream. One would have to make the ionic stream *I* appreciably larger than 10 ma.

It is understood that the opening in the wall (diaphragm) is to be considered as limit of the method of the present invention, in which thus the relationship $(1/d)$ moves towards 0. (Practically due to the always finite wall thickness is this ratio different from zero).

The form of the channel is to be selected in accordance with the statement above, if it has only a sufficiently large stream resistance. In addition to the mentioned cylindrically shaped channel, as a matter of course, also slot-shaped channels with a curved axis and the like can be used.

The production of the ionic current takes place in known manner for instance, by illuminous discharge, high-frequency discharge. Penning discharge, by electron discharge by means of a glowing cathode or by arch discharge. An embodiment by example by a one-step arrangement with high frequency is shown in FIG. 3. The arrangement comprises a recipient *R*, a

high frequency electrode *E*, an ionic channel *K*, electrodes *a*, *b*, *c*, *d*, *e*. The gas ionized in the space between *A* and *B* is sucked off by the extraction system *K*, *c*, *d*, *e*, and compressed in the space *B*, from which it is sucked off by a wort pump.

The channel of the extraction system is conically shaped relative to the bundle of the ions. By this arrangement, a concentration of the current and thereby an appreciable increase of the current flow through the channel is brought about. It is to be understood that also other focusing arrangements can be arranged for the concentration of the ionic current. In principle, they work all as electromagnetic lenses for the ion rays.

A further reduction of the return diffusion can be obtained by at least partly ionizing again the electrically neutral gas particles return diffused from *A* to *B* in the channel, whereby they are forced to reverse due to a simultaneously applied, for instance, electrical field. The ionization in the channel can take place again by high frequency alternating voltage (FIG. 4).

While I have disclosed several embodiments of the present invention, it is to be understood that these embodiments are given by example only and not in a limiting sense.

I claim:

1. An ion pump, comprising a housing having a first connection adapted to be connected to a vessel to be pumped and a second connection adapted to be connected to a wort pump, a glowing electron source disposed in said housing, a separating wall dividing said housing into a lower pressure chamber and a higher pressure chamber, a channel means disposed in said separating wall,

20 an anode catching electrons becoming free from said electron source, and cathodes connected to said higher pressure chamber, said electrons producing ions from gas from said vessel to be pumped,

25 said channel means being permeable for said ions and substantially nonpermeable for return diffusing gas, said ions being drawn in and by means of said channel means being led in the direction of said wort pump, a positive auxiliary electrode disposed in front of said first connection for said vessel to be pumped, which auxiliary electrode prevents a return diffusing of said ions into said vessel to be pumped,

30 an anode preset in front of said separating wall, and a high frequency alternating field applied in front of the entrance to said channel means in said lower pressure chamber between said preset anode and in and behind said channel means in said higher pressure chamber-connected cathodes so that particles of said gas do not enter a lower pressure in the space.

45 2. The ion pump, as set forth in claim 1, wherein said high frequency alternating field is connected at said channel means, so that said particles of said gas which are already in said channel means are ionized and guided back.

50 3. The ion pump, as set forth in claim 2, wherein said channel means in part is conically shaped relative to the path of said ions.

4. The ion pump, as set forth in claim 3, wherein said high frequency alternating field is connected at one end to said conically shaped part of said channel means and to the other end of said channel means.
